UNITED STATES PATENT OFFICE.

EDWARD BEECHER, OF THOMPSON, NEW YORK.

PULP-FEED REGULATOR.

1,088,670.

Specification of Letters Patent.

Patented Mar. 3, 1914.

Application filed July 3, 1911. Serial No. 636,577.

To all whom it may concern:

Be it known that I, EDWARD BEECHER, a citizen of the United States, residing at Thompson, county of Washington, and State 5 of New York, have invented certain new and useful Improvements in Pulp-Feed Regulators, of which the following is a specification.

The invention relates to such improvements and consists of the novel construction 10 and combination of parts hereinafter described and subsequently claimed.

Reference may be had to the accompanying drawings and the reference characters 15 marked thereon, which form a part of this specification. Similar characters refer to similar parts in the several figures therein.

Figure 1 of the drawings is a plan view of a pulp-box provided with my improved 20 means for regulating the outflow of pulp or stock therefrom. Fig. 2 is a vertical cross section of the same taken on the broken line 3--3 in Fig. 1. Fig. 3 is an end elevation of the same in connection with a conventional or diagrammatic representation of a 25 supply-pump. Fig. 4 is a side elevation of the pump.

My invention is adapted for regulating and controlling the outflow from any supply-box or reservoir, of liquid or partly-liquid fluid contents thereof.

The invention is particularly adapted for regulating and controlling the outflow from the pump-supplied pulp-box of an ordinary 35 paper-making machine; and in the drawings I have shown the invention applied to such a pulp-box.

The principal object of the invention is to provide for a continuous and uniform outflow from the box.

In supplying a pulp-box of a paper-making machine of the type to which my invention is shown applied in the drawings, the pulp is forced into the box through an opening in the bottom thereof by means of a pump at each stroke of which the level of the stock in the box rises somewhat, whereby the supply to the box is pulsatingly intermittent. In the preferred form of my invention, I utilize this pulsating variation in the level of the stock due to the pump-action to facilitate uniformity in the outflow of the pulp from the pulp-box at all times, while I also compensate for such variations or 55 changes in the level of the stock as are due

to variations in the consistency of the stock which affect its fluidity.

Referring to the drawings wherein the invention is shown in preferred form, 1, is the pulp-box divided by partitions, 2 and 3, into three compartments, one of which is a pulp-receiver, 4, supplied through a bottom-inlet, 5, with pulp from a pump, 37.

A weir is formed at, 6, in the partition, 2, over which the surplus stock flows into the waste-compartment, 7, from which it escapes through an outlet, 38, and is returned to the pulp-chest from which the pump derives its supply, said pulp-chest being omitted from the drawings, as the same forms no part of the present invention. The stock which is to be delivered to the paper-making machine, is permitted to flow out from the pulp-receiver, 4, through an outlet, 38, near the bottom thereof into the compartment, 9, 75 from which the stock flows through an outlet, 10, to the paper-making machine, not shown.

I have shown the outlet, 38, provided with a slide-valve or gate, 11, adapted to be operated by a hand-lever, 12, whereby the supply to the paper-making machine can be to some extent controlled; and also provided with an oscillating valve, 13, whereby, by means of my invention, said supply of stock 85 to the paper-making machine can be regulated and controlled with substantial accuracy to secure a uniform supply of pulp-fiber to the paper-making machine under different conditions of consistency of the 90 pulp or stock.

It is well understood in the art that pulp for the manufacture of paper varies more or less in consistency, and hence fluidity, and as the water is permitted to escape from the pulp in making the paper which is formed from the fiber of the pulp, it is necessary in order to secure paper of uniform weight or thickness that the supply to the paper-making machine should be substantially uniform in the quantity of pulp-fiber carried thereby. It thus becomes necessary to supply to the paper-making machine a greater quantity of thin pulp than of thick pulp for a given thickness or weight of paper.

It has been attempted to utilize changes in the level of pulp in the pulp-receiver to automatically operate a valve controlling the outflow to the paper-making machine, so that any considerable rise in the level of the stock 110

in the pulp-receiver due to an increase in the proportion of fiber whereby fluidity is reduced, would automatically induce a partial closing movement of said valve so as to permit less of the thicker pulp to pass thereby; but such devices have not been positive in response to the lesser changes in the level of the stock and hence were lacking in accuracy.

10 In carrying out my invention, I provide means whereby every change in the level of the stock in the pulp-receiver induces or causes a partial operation of the valve, 13, which I am able to do by employing mechanism which is not only responsive to the more considerable variations in level due to variations in the fluidity of the pulp, but is also responsive to the lesser variations in level due to the pulsations of the supply-pump, while at the same time a constant vibrating movement is imparted to the outlet valve which prevents clogging of the outlet-opening and assists the outflow of the pulp therethrough.

25 As a means for accomplishing the object of the present invention, I have shown the valve, 13, connected by an operating-link, 15, with one end of a lever, 16, pivoted or fulcrumed at, 17, upon a cross-bar, 18, extending across the top of the pulp-box, the other end of said lever being connected by a link, 19, with a float adapted to ride upon the top of the liquid-pulp in the pulp-receiver, 4. The connections thus established 30 between the float, 20, and valve, 13, are positive in their action so that each vertical movement of the float, 20, is immediately transmitted to the valve, 13. The float, 20, is constantly rising and falling in response to the 35 pulsations of the pump-supply, and this rising and falling of the float is transmitted to the valve, 13, in the form of a vibrating movement causing said valve to constantly oscillate or vibrate back and forth, thus 40 agitating the stock in the immediate vicinity of the valve and preventing the same from clogging the outlet opening.

Whenever the proportion of fiber in the stock is materially increased, the stock will 45 by reason of its less fluidity rise to a higher level causing the float, 20, to be correspondingly raised and the valve, 13, to be corre-

spondingly partly closed; and on the other hand, when the pulp contains less fiber, it will flow more freely over the weir, 6, thus lowering the level of the stock, permitting the float to descend and thereby impart to the valve, 13, a corresponding opening movement. It will be understood that to whatever degree the valve, 13, is effectively open, its constant oscillating or vibrating movement continues, due to the pump-pulsations. The link, 19, reciprocates through a guide, 21, swiveled at, 22, upon the cross-bar, 13. Each of the links, 15 and 19, is pivotally 55 and adjustably mounted upon the lever, 16, by means of a block, 23, swiveled upon the lever, 16, through which block the link passes, said block being confined between two nuts, 24 and 25, screwed upon the link 60 whereby vertical adjustment of the link can be accomplished. Longitudinal adjustment of the lever, 16, by which the leverage can be varied as desired to meet different conditions in use, is provided for by means of a 65 fulcrum-block, 26, through which the lever is adapted to slide, and an adjusting-screw, 27, which passes through a nut, 28, on the fulcrum-block and is rotatively mounted at, 29, and 30, upon the lever.

No detailed showing of the pump, 37, had been made as any of the known types of pulp-feeding pump may be employed.

What I claim as new and desire to secure by Letters Patent is—

In a paper making machine, a pulp box having an outlet; a valve controlling the outlet; a float; a lever; connections uniting the ends of the lever with the valve and with the float; a pivotally mounted fulcrum block 80 in which the lever is slidable, the lever having a pair of lugs located upon opposite sides of the block and between the connections; a screw threaded into the block and movable in the lugs, the screw extending upon both 85 sides of the block and constituting a truss for the lever; and nuts threaded upon the screw and adapted to engage the lugs.

In testimony whereof, I have hereunto set my hand this 24th day of June, 1911.

EDWARD BEECHER.
